CLAIM

The ornamental design for a network communication device, as shown and described.

DESCRIPTION

FIG. 1 is a front, top, and left perspective view of a network communication device;

FIG. 2 is a rear, bottom, and right perspective view thereof;

FIG. 3 is a top view thereof;

FIG. 4 is a bottom view thereof;

FIG. 5 is a right view thereof;

FIG. 6 is a left view thereof;

FIG. 7 is a front view thereof; and,

FIG. 8 is a rear view thereof.
